US0D1088028S

(12) **United States Design Patent** (10) Patent No.: **US D1,088,028 S**
(45) Date of Patent: **** Aug. 12, 2025**

(54) **DISPLAY SCREEN WITH GRAPHICAL USER INTERFACE**

(71) Applicant: **Hitachi High-Tech Corporation**,
Tokyo (JP)

(72) Inventors: **Fuka Matsudaira**, Tokyo (JP);
Takafumi Usui, Tokyo (JP); **Satoshi Yokotsuka**, Tokyo (JP); **Misato Fukami**, Tokyo (JP); **Yayoi Konishi**, Tokyo (JP); **Miyako Iida**, Tokyo (JP)

(73) Assignee: **Hitachi High-Tech Corporation**,
Tokyo (JP)

(**) Term: **15 Years**

(21) Appl. No.: **29/918,610**

(22) Filed: **Nov. 29, 2023**

(30) **Foreign Application Priority Data**

May 30, 2023 (JP) ..... 2023-010979 D

(51) **LOC (15) Cl.** **14-04**

CLAIM

The ornamental design for a display screen with graphical user interface as shown and described.

DESCRIPTION

The sole FIGURE is a front view of a display screen with graphical user interface according to the design.

The outermost broken line rectangle illustrates the display screen and forms no part of the claimed design. All text shown in broken lines illustrate portions of the graphical user interface that form no part of the claimed design.

1 Claim, 1 Drawing Sheet
